DESIGN FOR A HAT OR SIMILAR ARTICLE

Raymond S. Glassheim and Jerome Weinstein,
Forrest Hills, N. Y.

Application March 23, 1941, Serial No. 99,953

Term of patent 3½ years

To all whom it may concern:

Be it known that we, Raymond S. Glassheim and Jerome Weinstein, both citizens of the United States, both residing at Forest Hills, in the county of Queens and State of New York, have invented a new, original, and ornamental Design for a Hat or Similar Article, of which the following is a specification; reference being had to the accompanying drawing, forming part thereof.

Fig. 1 is a perspective view of a hat or similar article, showing our new design.

Fig. 2 is a rear view thereof on a smaller scale.

The characteristic feature of our design resides in the combination, on the hat disclosed, of the looped yarn tieing ends, as shown.

We claim:

The ornamental design for a hat or similar article, substantially as shown and described.

RAYMOND S. GLASSHEIM.
JEROME WEINSTEIN.
